[57] CLAIM

The ornamental design for a shelf unit, as shown and
described.

DESCRIPTION

FIG. 1 is a front elevational view of a shelf unit showing
my new design;

FIG. 2 is a right side elevational view, the left side being
a mirror image thereof;

FIG. 3 is a perspective view, the opposite side being a
mirror image thereof; and

FIG. 4 is an enlarged fragmentary front elevational
view of the left corner.
